UNITED STATES PATENT OFFICE.

ALBERT CHALLEEN, OF MINNEAPOLIS, MINNESOTA.

COMBINATION MAIL AND PARCEL-POST BOX.

1,137,740.

Specification of Letters Patent.

Patented May 4, 1915.

Application filed March 23, 1914. Serial No. 828,495.

To all whom it may concern:

Be it known that I, ALBERT CHALLEEN, residing at 701 University avenue south-east, in the city of Minneapolis, county of 5 Hennepin, and State of Minnesota, have invented a new and useful Improvement in Combination Mail and Parcel-Post Boxes, of which the following is a specification.

The present invention relates to improvement in a combination mail and parcel post box.

The object of this device is to provide a safe and serviceable receptacle for United States mail and parcel post, especially adapted to the needs of persons living along the rural free delivery routes, where it may be attached to a post or otherwise secured near the roadway within convenient reach of the mail carrier.

For a full understanding of the present invention, reference is to be had to the following description and the accompanying drawing and specifications.

Figure 1 is a transverse section of the receptacle taken at about the line 8—8 Fig. 2 showing the mail and parcels compartments and embodying the present invention. Fig. 2 is a front view showing the doors to the different compartments and the general 30 shape and arrangement of the mail and parcels compartments. Fig. 3 is a sectional view showing the doors partially opened and exhibiting the method of hinging whereby practically weather proof joints are obtained. Fig. 4 is a perspective view of the door to the upper compartment showing its construction in detail. Number 1 refers to the straight front portion of the door, number 1' refers to the flanges through which 40 the rivets 6 on which the door is pivoted pass, and number 1'' refers to the bottom of the door turned up so as to present a convex surface on its lower side, which moves in a concave depression or groove in the rigid partition numbered 10. Fig. 5 is a perspective view of the door to the lower compartment showing its construction in detail. Number 3 refers to the straight outer portion of the door to the lower or parcel 50 compartment, and number 3' refers to the flanges through which the rivets 7 on which the door is pivoted pass.

Throughout the following detailed description and on the several figures of the drawings, similar parts are referred to by 55 like reference characters.

Specifically describing the said combination mail and parcel post box as constructed in accordance with my invention, the numerals 1, 1' and 1'' designate the door to the upper or mail compartment, 1 referring to the straight front portion 1'' referring to the curved portion articulating with the socket or groove in the bottom or partition 10 between the mail and parcel post compartments, 1' refers to the flanges of the door moving against the sides of the receptacle. In closing the door 1 swings on the pivot 6, until the rounded edge of 1 strikes the ridge 4 which extends across the arched roof of 70 the mail compartment and prevents further movement, 1 is then engaged and held closed by the notched spring 5.

Numerical 3 refers to the straight portion of the door to the lower or parcel compartment with flanges 3' which move against the sides of the lower compartment. In opening the door 3 swings upward on pivot 7, and when closed the upper edge of the door is pressed against the overlapping portion 80 of wall 2, and the lower end of the door makes contact with the bottom 9 in which position it is held by its own weight.

I am now aware that prior to my invention combination mail boxes adapted for 85 mail and parcels have been made, having an upper and lower chamber separated by a rigid partition forming the bottom and the top of the upper and lower chambers respectively and having hinged doors opening 90 at the end of said chambers, I do not therefore claim such combination broadly; but—

I claim:

1. The combination, in a mail and parcel post box having a rigid middle partition 95 with a groove or concave depression separating the upper, mail compartment, and the lower parcel compartment, of an upper door with convex bottom articulating or moving in the groove or concave depression in the 100 said rigid partition, when swung up or down on its pivots, producing a practically weather-proof hinge substantially as described.

2. In a combination mail and parcel post box, having a rigid middle partition with a groove or concave depression separating the upper, mail compartment, and the lower
5 parcel compartment, the combination of an upper door with a convexly curved bottom, forming a rounded surface running along the bottom of said door, so pivoted that

when swung open or shut said convex surface moves in the groove or depression in 10 the said rigid partition substantially as described.

ALBERT CHALLEEN.
